UNITED STATES PATENT OFFICE.

SIDNEY S. GROTTA, OF HARTFORD, CONNECTICUT.

WRAPPER.

1,275,904.

Specification of Letters Patent. Patented Aug. 13, 1918.

Application filed July 17, 1916. Serial No. 109,730.

To all whom it may concern:

Be it known that I, SIDNEY S. GROTTA, a citizen of the United States, residing at Hartford, in the county of Hartford and State of Connecticut, have invented new and useful Improvements in Wrappers, of which the following is a specification.

This invention relates to a wrapper for wrapping articles of various kinds, more particularly candy, gum and other objects. In the case of gum, single sticks are wrapped up in tin foil, and then are covered with a tube of paper formed from a sheet. This cover reaches closely to the ends of the gum, in order that the package shall appear attractive.

A number of these sticks are then wrapped up in a package by means of a second sheet formed into a tube, this outer sheet holding the several single sticks together in one package, and thus covering the inner sticks close to their ends. It is difficult to remove one of the sticks from such a package, and it is also difficult to remove the single stick from the single package, without tearing the outer cover.

The object of this invention is to provide a wrapper for a single stick or article, so as to enable that article to be removed from its cover or tube readily. It also has for its object the removing of single sticks from a package of wrapped sticks, or articles. I carry this out by means of the following devices:—

Figure 1 shows a wrapper laid out flat for a single article. Figs. 2 and 3 show edge and top views respectively, of an article wrapped with the wrapper of Fig. 1.

Fig. 4 shows a sheet for wrapping a series of articles. Figs. 5 and 6 show edge and top views, respectively, of a series of articles wrapped as shown in Figs. 2 and 3, when the sheet is made into a tube.

Fig. 7 shows the package of Fig. 5 with one of the articles slid endwise partly from the package.

Fig. 8 shows the manner of removing a stick from the package of Fig. 6.

Fig. 9 shows an edge view of the article of Fig. 2, partly removed from its wrapper. Fig. 10 shows a view of Fig. 9, and the manner in which the article is removed from its wrapper.

It is desirable that the package on its top side, as shown in Fig. 3, where a single article is wrapped, and also on its top side as

shown in Fig. 6, where a series of articles are wrapped, should cover as much of the article as possible. For that reason the outer wrapper is kept equal to the full length, or nearly to the full length of the inclosed article.

12 shows the wrapper laid out flat, and having two notches 13 and 14, and two flaps 15 and 16. The wrapper 12 is wrapped around the article 18, as shown in Figs. 2 and 3. The wrapper is this instance, is a little shorter than the article to be wrapped, although the wrapper may be equal to the length of the article, which in some instances may be preferred.

The wrapper 12 is so folded around the article that the notches 13 and 14 are disposed at the edges of the article 18, so that the flap portion 16 projects beyond the bottom 19 of the notches, and thus serves to cover over the article 18 on top and bottom close to its end, but leaving an exposed portion 20—20 at each edge of the article 18.

By seizing the edge of the wrapper of a single stick by fingers 21—21, as shown in Fig. 10, and also seizing article 18 by the fingers 22—22, at the exposed portions 20 of the article, the latter may be readily slid endwise out of the tube 12.

25 represents an outer wrapper, being notched at 26—27, and having intermediate flaps 28 and 29. This wrapper 25 is wrapped around a series of articles, as for example five wrapped articles 18, as shown in Figs. 5 and 6, the outer wrapper being formed into a tube and pasted together so as to hold these articles together.

The flap portions 28, 29, are placed over the top and bottom of the package, shown in Fig. 6, and the notched portions 26—27 come opposite to each other, thus exposing the edges of the articles 18, wrapped in their wrappers 12.

The wrapped articles of Fig. 2 are placed in the outer tube with their notched exposed edges 20 beneath the left hand end 30 of the wrapper 25 of Fig. 5, so that these notched edges of the single articles, are not exposed. The opposite covered edges 32 of the single articles of Figs. 2 and 3 are, however, exposed when wrapped in the tube of Figs. 5 and 6.

The object of this arrangement is to enable one single article with its wrapper to be removed from the package of Figs. 5 and 6, without pulling the article itself out of

its own wrapper, which would be the case if the notched edges of both covers were placed at the same end of the package.

Fig. 7 shows one wrapped article 18 with its tube being removed from the package of five wrapped articles, and this is accomplished by grasping the whole package by the fingers 35 and 36, and then grasping the exposed edge 32, 32 of one of the articles 10 by means of the fingers 37 and 38.

The invention claimed is:—

1. A wrapper for gum and confections comprising a wide and thin paper tube that is open at both ends, is oblong in transverse section, and that for a short distance back from one end has its narrow side walls and also portions of its wide front and back walls adjacent to the side walls, cut away so that the edges and small sections of the 15 top and bottom near the edges of a thin article inclosed by the tube will be exposed and may be grasped for withdrawal from the tube without gripping the wrapper forming the tube.

2. A series of wrappers formed of a series

of sheets, and folded into tubes, each around an article, one end of each tube having two oppositely cut away notches, and two intermediate flaps between the notches; combined with a second outer sheet folded into a 30 tube around said series of wrapped articles, said latter tube having two oppositely cut away notches and two intermediate flaps between the notches.

3. A series of wrappers formed of a series of sheets, and folded into tubes, each around an article, one end of each tube having two oppositely cut away notches, and two intermediate flaps between the notches; combined with a second outer sheet folded into a tube 40 around said series of wrapped articles, said latter tube having two oppositely cut away notches and two intermediate flaps between the notches, said notches and flaps being placed opposite to and endwise of the notches of the inner wrapped articles; the cut away notches of the inner wrapped articles being covered by the uncut end of the 45 outer tube.

SIDNEY S. GROTTA.
